UNITED STATES PATENT OFFICE.

JOHN RALPH VAN DUYNE, OF WHITE PLAINS, NEW YORK.

CONTOUR-INTERPOLATOR.

986,248.

Specification of Letters Patent.

Patented Mar. 7, 1911.

Application filed January 20, 1910. Serial No. 539,057.

To all whom it may concern:

Be it known that I, JOHN RALPH VAN DUYNE, a citizen of the United States, and a resident of White Plains, in the county of 5 Westchester and State of New York, have invented a new and Improved Contour-Interpolator, of which the following is a full, clear, and exact description.

The invention relates to drafting instruments, and its object is to provide a new and improved interpolator, more especially designed to interpolate between two elevations plotted in plan points on any required intervening contours.

For the purpose mentioned, use is made of a base plate having a straight edge, an arm intersecting the straight edge, and a carrier capable of moving on the said plate and on which the said arm is mounted.

A practical embodiment of the invention is represented in the accompanying drawings forming a part of this specification, in which similar characters of reference indicate corresponding parts in all the views.

Figure 1 is a plan view of the contour interpolator; Fig. 2 is an under side view of the graduated slide; Fig. 3 is an enlarged cross section of the base plate on the line 3—3 of Fig. 1; and Fig. 4 is a similar view 30 of the same on the line 4—4 of Fig. 1.

The base plate A of the contour interpolator is provided with a straight edge B, preferably made of celluloid or other transparent or translucent material, and on the upper face of the base plate A is secured or formed a guideway C, preferably disposed diagonally and in which is slidably mounted a graduated slide D, provided along its sides on both faces with graduations D', D² and 40 D³, D⁴, as plainly indicated in Figs. 1 and 2, it being understood that the slide can be reversibly placed in the guideway C, to bring either face of the slide to the top. The graduations represent equal divisions, 45 from zero to 25 on one face and from zero to 50 on the opposite face, the graduations D' and D² being in the reverse order, and similarly the graduations D³, D⁴. Lines C', C² are placed on the upper end of the guideway C and are setting lines for the graduations D', D², D³, D⁴. On the straight edge B is a starting point B' intersected by the continuation of the lines C', C², as will be readily understood by reference to Fig. 1.

On the guideway C is mounted to slide a carrier E, having its front edges E', E²

adapted to indicate on the marks of the graduations D', D², D³, D⁴, and the said carrier E is provided with a spring F, bearing on one side of the guideway C, so as to 60 take up lost motion of the carrier E on the guideway C. The carrier E is provided with a lug E³, engaged by a clamping bolt G, on which is mounted to swing an arm H, extending over the face of the plate A and intersecting the straight edge B. The axis of the clamping bolt G is intersected by the front edge of the arm H, and the front edges E', E², and the axis also extends through a line running parallel with the guideway C 70 and passing through the starting point B' on the straight edge B. Now when two elevations are given on a chart, map or the like, and it is desired to interpolate between the points, then the plate A is placed in position, so that the straight edge B extends from one point to the other with one point at the starting point B'. Assume the elevation at the starting point B' to be 321.6 and the other given elevation to be 329.4 and let 75 it be required to interpolate for points 328, 326, 324 and 322. Keeping the base plate in the position above stated and using the graduations D², move the slide D until the point 1.6 tallies with the setting line C², 80 then move the carrier E until the setting edge E² tallies with 9.4, now swing the arm H attached to the carrier E until its front edge intersects the given elevation point 329.4, clamp the arm H fast to the carrier E, so that the arm H moves bodily with the carrier E, and the interpolator is entirely set to obtain the required points, now push the carrier E along until the setting edge E² 85 tallies with Fig. 8 on the graduations D², 90 then the intersection of the front edge of the arm H with the straight edge B gives one of the required points which is marked with a lead pencil; in like manner push the carrier E along until the setting edge E² 95 tallies with Fig. 6 on the graduations D², 100 and mark intersections as before, and another required point is obtained, and so on, for points corresponding to Figs. 4 and 2.

The instrument is very simple and durable in construction and can be cheaply manufactured and readily used for accurately interpolating between two elevations.

Having thus described my invention, I claim as new and desire to secure by Letters 110 Patent:

1. A contour interpolator, comprising a

base plate having a straight edge, a graduated scale arranged on the base plate diagonally to the straight edge, a carrier mounted on the base plate to travel over 5 the scale, and an arm pivoted at one end to the carrier and intersecting the said straight edge.

2. A contour interpolator, comprising a base plate having a marking edge, a carrier 10 slidable on the base plate diagonally to the marking edge thereof, an arm adjustably mounted on the carrier and extending across the marking edge, and a graduated scale 15 slidably mounted on the base plate and over which the carrier slides.

3. A contour interpolator, comprising a base plate having a straight edge and a guideway diagonal to the straight edge, a graduated slide movable in the said guideway, a carrier slidable on the said guideway, 20

an arm intersecting the said straight edge and pivoted on the said carrier, and means for fastening the said arm in position on the said carrier, to move bodily with the latter.

25

4. A contour interpolator, comprising a base plate having a straight edge, and a guideway extending diagonally of the base plate, a graduated slide in the guideway, a carrier slidable on the guideway, and an arm pivoted to the carrier and projecting 30 beyond the straight edge of the base plate.

In testimony whereof I have signed my name to this specification in the presence of two subscribing witnesses.

JOHN RALPH VAN DUYNE.
